UNITED STATES PATENT OFFICE

JOHN T. GLEKLER, OF CLEVELAND, OHIO, ASSIGNOR TO THE OHIO CHEMICAL & MANUFACTURING COMPANY, OF CLEVELAND, OHIO, A CORPORATION OF OHIO

APPARATUS FOR PACKAGING LIQUIDS

Application filed June 29, 1926. Serial No. 119,297.

This invention relates to packaging ether or other liquids in an atmosphere of carbon dioxide, nitrogen or other gas or gases, preferably inert, and its chief object is to provide for the purpose an apparatus of simple and durable construction by which the various operations can be performed rapidly and efficiently. Another object is to provide an apparatus by which the amount of liquid per can is automatically measured, so that all cans of a given size and shape will contain substantially the same amount. To these and other ends the invention comprises the novel features and combinations hereinafter described.

In carrying out the invention in the preferred manner I provide a pair of three-way valves of the rotary plug type, preferably combined in one structure and operated by a single handle. The inlet port of one valve is connected with a source of ether, while one outlet port is connected to an inlet or filling tube to discharge into the can and the other is connected with an overflow pipe for discharge of ether from the can until the predetermined amount is left in the can. The other valve has its inlet port connected with a source of carbon dioxide, while one outlet port is connected with the aforesaid overflow pipe and the other is connected with a pipe for discharging the carbon dioxide into the can. Means are also provided for holding the can in operative position with respect to the valves, so that by proper manipulation thereof the operator can first fill the can or other receptacle with carbon dioxide to purge the same of air, then fill the can with ether, driving out all the carbon dioxide, then admit carbon dioxide again to drive out a portion of the ether and leave only a predetermined quantity therein.

The embodiment outlined above is illustrated in the accompanying drawings, in which

Fig. 1 is a side view of the complete apparatus.

Fig. 2 is a front view of the table for supporting the can.

Fig. 3 is a detail side view of the filling valve, on a larger scale, and Fig. 4 is a rear

view of the same with the upper and middle brackets, and the ether and carbon dioxide supply pipes, in section on line 4—4 of Fig. 1.

Figs. 5, 6 and 7 are diagrammatic views in horizontal section, showing the different positions of the valve in the filling operation. In these figures the upper sections are taken on line a—a and the lower sections on line b—b of Fig. 3.

The standard 10, vertically adjustable in the base 11, has an upper bracket 12 provided with a clamping ring 13 in which the filling valve 14 can be clamped by means of the binding bolt 15. The base also carries a vertically movable stem 16 carrying a table 18 for the can 19 which is to be filled.

The stem 16 and table 18 are raised by two pairs of toggles 20, 21, pivoted at the top to the head 22 of the stem 16 and at the bottom to the guide 24 on the base 11. The center joints of the toggles are connected by contractile springs 25, 26, which urge the toggles toward straight position, thereby raising the stem and table, as will be readily understood.

Between the bracket 12 and table 18 the standard is provided with an arm 30 having in its outer end a downwardly open socket 31 to receive the neck of the can 19 and having a yielding gasket 32 to make a gas-tight joint with the edge of the neck when the can is in filling position.

The valve 14 comprises a casing 33 and a tapered plug 34 which can be rotated by a handle 35. The plug has an upper angular transverse passage 36, to cooperate with an ether inlet or supply pipe 37 connected with the ether receptacle not shown, an ether delivery pipe 38 for conveying ether into the can, and an overflow pipe 39 for carrying away ether expelled from the can, these three pipes being hermetically fitted to apertures in the valve casing. The plug also has a lower angular passage 40 to cooperate with a carbon dioxide supply pipe 41 connected with the cylinder of carbon dioxide under pressure, not shown, a carbon dioxide delivery pipe 42 for conveying the gas to the can, and a carbon dioxide overflow or discharge pipe 43 for carrying away gas expelled from the can. The pipes 41, 42, 43 are hermetical-

ly fitted to suitable apertures in the valve casing, and in addition pipe 43 may be connected to pipe 39, as indicated. Pipes 38 and 42 extend into the socket 31 in arm 30 and are sealed in place.

6 The filling operation will now be readily understood.

7 The supply pipes 37, 41 being connected respectively to a source of ether and to a source of carbon dioxid (CO_2) under suitable pressure, and the valve being in the "off" position, Fig. 5, the operator depresses the table 18, places a can thereon in position to receive the pipes 38 and 42, and then allows the table to rise. This causes the pipes 38 and 42 to enter can 19 and seals the neck of the latter by pressing it against the gasket 32. The operator now gives the valve a quarter turn to the position represented in Fig. 6, in which the ether supply pipe 37 is still closed but the CO_2 pipe 41 is connected with pipe 42 through valve passage 40. Carbon dioxid then enters the can 19 in the form of a jet, strikes the bottom of the can and expands radially, and rising in the can drives air out ahead of it through pipe 38, valve passage 36, and pipe 39. It will be understood that this operation is very rapid, so that only a momentary holding of the valve in the position of Fig. 5 is necessary. The valve is then turned a quarter of a revolution to the position of Fig. 7. Ether now enters the can through valve passage 36 and pipe 38, expelling the carbon dioxid through pipe 42, valve passage 40, pipe 43 and pipe 39. As soon as the rising ether reaches the pipe 42 it begins to rise therein and then issues through valve passage 40 and pipe 39 into a suitable receptacle, not shown. The operator then knows that can 19 is filled with ether and emptied of carbon dioxid, whereupon he gives the valve a quarter turn back to the position of Fig. 6. Carbon dioxid now enters by way of passage 40 and pipe 42, and forces ether out through pipe 38, valve passage 36 and pipe 39, until the ether in can 19 has fallen to the bottom of pipe 38, after which carbon dioxid enters the latter pipe. When the flow of ether through pipe 39 ceases, the operator gives the valve a quarter turn back to the "off" position, Fig. 5, depresses the table 20, removes and seals can 19 or passes it on to another person for sealing, puts another can on the filling table, and the cycle described is then repeated.

8 It will be observed that the depth of the ether left in the can when it is removed for sealing depends upon the height of the bottom of the pipe 38 above the bottom of the can when the neck of the latter is pressed up in the socket member 31. The latter may thus serve as a stop for the can. Hence if the cans are all of uniform size and shape they will all have the same quantity of ether, with the same volume of CO_2 above. This is an

automatic measuring, the accuracy of which is virtually independent of the operator's judgment. The operator can therefore work rapidly, with the assurance that the machine is responsible for the accuracy of the measurements.

9 In the embodiment illustrated the amount of ether finally left in the can depends upon the size and shape of the can, and to vary the amount it is necessary to vary one or another of these factors, unless the length of the pipe 38 is altered. If the height of the can is changed materially the standard 10 may be adjusted vertically to compensate for the change and keep the elongation and contraction of the springs approximately the same as before. The lifting effort of the springs depends upon their tension. The springs at one end are connected directly to the toggle pivots 45. At the other end they are connected to short rods 46 passing through the toggle pivots 47 and threaded into stop-nuts 48, so that by adjusting the latter the tension can be regulated. The upper position of the table 18 may be determined by an adjustable collar 49 encircling stem 16 below the base 11 and secured in adjusted position by a set screw 50.

10 It is to be understood that the invention is not limited to the specific construction herein illustrated and described but can be carried out in other ways without departure from its spirit. Nor is the invention in use confined to filling containers with ether, but may be employed with other liquids and other gases.

11 I claim—

12 1. In a filling apparatus, in combination, relatively movable upper and lower members one to support a container and the other to close the filling aperture thereof, piping associated with said upper member to carry gas to and from the container through its filling aperture while the same is closed by said upper member, piping associated with the upper member to carry liquid to and from the container through the filling aperture while the same is closed by said upper member, piping to convey gas and liquid to the first and second mentioned piping, and valve means connected with all said piping to permit delivery of gas and liquid in succession but not simultaneously to the container.

13 2. In a filling apparatus, in combination, relatively movable upper and lower members one to support a container and the other to close the filling aperture thereof, piping associated with said upper member to carry gas and liquid to and from the container through its filling aperture while the same is otherwise closed by said upper member, and a valve having ports connected with the piping and having a manually operable member provided with passages cooperating with said ports and adapted in one position to pass gas into the container and gas or liquid out of the

container through a portion of said piping and in another position to pass liquid into and gas out of the container through a portion of said piping.

5. In a filling apparatus, in combination, an inlet pipe for delivering liquid to a container, an inlet pipe for delivering a gas to the container, valve means operable at will and having passages to open the pipes singly to admit liquid or gas through the respective pipes but not through both simultaneously, and a liquid overflow pipe connected with said valve means; said valve passages also cooperating with the overflow pipe for outflow of gas while liquid is entering the container and outflow of liquid while gas is entering the container.

4. In a filling apparatus, in combination, an inlet pipe adapted to enter a container for delivering liquid thereto, an inlet pipe for delivering a gas to the container, valve means operable at will to open the inlet pipes singly to admit liquid or gas through the respective pipes but not through both simultaneously, 20 pipes for connecting said valve means respectively with a source of the liquid and with a source of the gas under pressure, a liquid overflow pipe connected with said valve means for outflow of gas or liquid from the container, said valve means being adapted to permit outflow of gas through the overflow pipe while liquid is entering the container and outflow of liquid through the overflow pipe while gas is entering the container; and 25 means for holding the container in filling position with the liquid inlet pipe extending a predetermined distance into the container.

5. In a filling apparatus, in combination, an inlet pipe for delivering liquid to a container, an inlet pipe for delivering a gas to the container, a liquid supply pipe, a gas supply pipe, pipe means for carrying gas and liquid away from the container, and valve means having passages to put the gas supply pipe in communication with the gas inlet pipe and put the liquid inlet pipe in communication with the pipe means when the valve means is in one position, and to put the liquid supply pipe in communication with the liquid inlet pipe and put the gas inlet pipe in communication with the pipe means when the valve means is in another position.

6. In a filling apparatus, in combination, an inlet pipe for delivering liquid to a container; an inlet pipe for delivering a gas to the container; a liquid supply pipe; a gas supply pipe; pipe means for carrying gas and liquid away from the container; valve means having passages to put the gas supply pipe in communication with the gas inlet pipe and put the liquid inlet pipe in communication with the pipe means when the valve means is in one position, and to put the liquid supply pipe in communication with the liquid inlet pipe and put the gas inlet pipe

in communication with the pipe means when the valve means is in another position, and means for holding the container in filling position with the liquid inlet pipe extending a predetermined distance into the container.

7. In a filling apparatus, in combination, 70 an inlet pipe for delivering liquid to a container having a filling opening, an inlet pipe for delivering a gas to the container, a liquid supply pipe, a gas supply pipe, pipe means for carrying gas and liquid away from the container, valve means having passages to put the gas supply pipe in communication with the gas inlet pipe and put the liquid inlet pipe in communication with the pipe means when the gas means is in one position, and to put the liquid supply pipe in communication with the liquid inlet pipe and put the gas inlet pipe in communication with the pipe means when the valve is in another position, 75 a support for holding the container in filling position with the liquid inlet pipe extending through the filling opening a predetermined distance into the container, and means serving to seal the filling opening during the filling operation.

8. In a filling apparatus, in combination, 80 a delivery pipe adapted to be inserted in a container, a liquid supply pipe, a liquid overflow pipe, a two-way valve for putting the delivery pipe in communication with either the supply pipe or the overflow pipe at will, and valve controlled means for delivering gas under pressure to the container.

9. In a filling apparatus, in combination, 85 a liquid delivery pipe adapted to be inserted in a container through the filling aperture thereof, a gas delivery pipe for delivering gas to the container through its filling aperture, means for closing the filling aperture to liquid and gas except through said pipes, a liquid supply pipe, a gas supply pipe, a liquid overflow pipe, and a valve having groups of ports connected with the supply, delivery, and overflow pipes and having a manually operable member provided with a two-way passage cooperating with one group of ports to convey gas from the gas supply pipe to the gas delivery pipe or convey gas from the gas delivery pipe to the overflow pipe, and provided 90 with a two-way passage cooperating with another group of ports to convey liquid from the liquid supply pipe to the liquid delivery pipe or convey gas from the latter pipe to the overflow pipe.

10. In a filling apparatus, in combination, 95 a liquid supply pipe, a gas supply pipe, a liquid discharge pipe adapted to extend into the filling aperture of a container, a gas discharge pipe, means to cooperate with the filling aperture of the container to prevent inflow or outflow of gas and liquid except through said discharge pipes, a gas and liquid overflow pipe, and valve means between the
